UNITED STATES PATENT OFFICE.

ARTHUR H. HUTCHINSON, OF ATLANTA, GEORGIA.

ICE-MAKING APPARATUS.

Application filed April 19, 1924. Serial No. 707,687.

To all whom it may concern:

Be it known that I, ARTHUR H. HUTCHINSON, a citizen of the United States, residing at Atlanta, in the county of Fulton and State of Georgia, have invented certain new and useful Improvements in Ice-Making Apparatus, of which the following is a specification, reference being had to the accompanying drawings.

10 This invention relates to ice making apparatus and more particularly to a cross bar for maintaining the cans employed for holding the water in ice making apparatus submerged as the water contained in the can is frozen.

An important object of the invention is to combine the construction of a hold-down bar of this type with the can dog ordinarily employed for elevating the can from the brine tank and supporting the can during its transportation to the thawing apparatus.

A further object of the invention is to provide a device of this character which when used with cans employing raw water in ice making likewise forms a support for the air pipe ordinarily employed to agitate the water while freezing to prevent the formation of white ice.

A further and more specific object of the invention is to provide a bar provided at each end thereof with a pair of dogs, one dog at each end being employed to engage the walls of the compartment in which the ice can is disposed to prevent upward movement of the can, the other of the dogs of each pair being adapted to engage in the walls of the can during hoisting of the can so that the bar may be employed to elevate the can as well as hold the can submerged.

40 A still further object of the invention is to provide a device of this character which is capable of a great range of change and modification in its construction so that it may be readily adapted to the construction of various types of ice cans and compartments in which the cans are to be disposed.

These and other objects I attain by the construction shown in the accompanying drawings, wherein for the purpose of illustration is shown a preferred embodiment of my invention and wherein:—

50 Figure 1 is a sectional view showing a combined hold-down bar, air tube support and can dog constructed in accordance with my invention applied to a can, the portions

of the bar being broken away to show the construction thereof;

Figure 2 is a section on the line 2—2 of Figure 1;

Figure 3 is a sectional view through the 60 dog showing a front elevation of the hold-down pawl;

Figure 4 is a sectional view showing a modified pawl construction;

Figure 5 is a view showing the mounting 65 of the air pipe in a type of bar construction shown in Figures 4 and 6;

Figure 6 is a section taken through the pawls of this type of bar;

Figure 7 is a further modified construction in which two pawls are constructed integrally;

Figure 8 is a further modification of this type of pawl construction;

Figure 9 is a side elevation showing a further modification of the two pawl structure;

Figure 10 is a vertical sectional view showing a preferred manner of mounting the air pipe in the bar when the bar is 80 of solid construction;

Figure 11 is a transverse sectional view taken through this type of mounting immediately above the bar;

Figure 12 is a view showing a preferred manner of mounting the air pipe in constructions where the bar is of a channel type, a portion of the bar being broken away;

Figure 13 is a vertical sectional view through the type of construction shown in Figure 12.

Referring now more particularly to the drawings, the numeral 10 indicates the body of an ice can, 11 the reinforcing band applied about the upper surface of the body, and 12 the openings formed in opposite 85 walls of the can for the reception of the lugs of an ordinary can dog (not herein disclosed). The numeral 13 designates the walls of the compartment in which the can is disposed during operation of freezing of the contents, these walls being usually formed by partitions subdividing a large tank (not shown) into a plurality of compartments. It will be obvious that the tank below a level generally designated at 14, is 100 filled with brine or other cooling medium in which the can is submerged. It will be obvious that when the can is filled with clear water, the can itself being constructed of metal, this can will readily submerge in the 110

brine for the major portion of its length. In the usual construction the can is then forced downwardly and held in position by a cross bar disposed across the top of the can.

5 In accordance with my invention I provide a cross bar 15 which may be of varied construction but which in all constructions includes a body portion 16 of a length equal to the inside width of the can having except in that form of the invention shown in Figure 1 at its upper edges extensions 17 adapted to rest upon the upper surface of the can. In Figure 13 I have illustrated a cross bar formed of channel iron, the channel being upwardly directed, in Figure 7 a cross bar formed of wood, and in Figure 6 a cross bar formed of two spaced angle irons secured together centrally by a plate 18. In all constructions of the cross bar this bar is provided intermediate its ends and preferably centrally thereof with an opening permitting passage of an air tube 19 when such tubes are employed with the tank with which the bar is to be used. In the first two constructions mentioned the openings permitting the passage of the air tubes 19 are formed directly in the bars, while in the construction employing the two angle iron bars the connecting plate 18 is formed with this opening. The means of mounting the air tube in this opening may be of any desired character but in each instance the air tube will preferably be provided adjacent its upper end with a collar 20 limiting its downward movement through the opening.

Carried by each end of the cross bar is a lifting pawl 21, this pawl having a nose 22 adapted for engagement in the can dog openings 12 of the can 10. This dog is likewise capable of a considerable range of change and modification. In Figure 8 I have illustrated a dog pivoted to the bar, as at 23, and having a weighted upper end 24 normally maintaining it out of engagement with the can dog openings of the can. In this form of dog construction the weighted upper end is provided with an opening 25 for the reception of the hooks 26 at the ends of diverging chains 27 of hoisting apparatus by means of which the can is hoisted from the compartment when the contents thereof are frozen or by means of which the can is lowered into the compartment primarily. These hooks are two in number and are connected by chains to a single ring so that the hooks tend to move toward one another when strain is placed thereon and by this tendency will draw the weighted upper ends of the dogs toward one another and force the noses 22 of the pawls into the can dog openings.

The bar 15 is, of course, always applied to the can in one general position, that is to say, in a position where it bridges the can in alignment with the can dog openings, and since these cans are rectangular in cross section the ends of the bar will always be opposed to corresponding points of two opposed walls 14 of the compartment. In or on these walls immediately above the upper surface of the can when submerged the proper distance in the brine of the tank I provide a downwardly facing shoulder 28. In Figure 8 this shoulder is formed by notching the walls 14 and reinforcing the walls of the notch as indicated at 29. In Fig. 1 a shoulder is provided by securing to the wall a plate 30 the under surface of which provides a shoulder 28, while in Figure 4 a combination of these two constructions is employed. Upon the weighted upper end of the pawl I preferably provide a hold-down nose 31 which by the weight of this upper end is held beneath this shoulder to prevent upward movement of the bar and accordingly of the can. It will thus be seen that the dog 21, together with its weighted upper end 24, in reality comprises a pair of dogs, one coacting with the notches or openings of the cans and the other coacting with the downwardly facing shoulders of the compartment walls.

In Figure 7 a slight modification of this structure is resorted to. The same general type of dog construction is employed but to insure against accidental disengagement of either the can engaging nose or the shoulder engaging nose of the combined pawl, a spring 32 is secured to the bar 15, this spring having a portion 33 extending into the path of the dog 21 and against which this dog engages before the nose 22 thereof is withdrawn from the opening 12 and a second portion 34 aligning with the weighted upper end 24 and against which this upper end engages prior to its disengagement from beneath the shoulder 28.

In Figure 9 is illustrated one form of dog wherein the weighted upper end 24 and the pawl 21 are formed in two sections, the pawl 21 being bifurcated at its upper end to produce a pair of arms 35 through which the pivot 23 is directed. The weighted upper end 24 is mounted upon this pivot intermediate these arms, as shown, and has projecting from the sides thereof a pin 36 extending into a notch 37 formed in the upper edge of the arm 35. The nose 22 of the pawl 21 engages in the can dog opening by gravity when the bar is placed in position and the weighted upper end 24, because of its unbalanced weight, engages its nose 31 beneath the shoulder 28 as the can is settled into position in the compartment. When the hooks of the hoisting apparatus are engaged in the openings of the weighted upper end to hoist the can, this weighted upper end is swung toward the center of the bar so that the pin 36 engages against the inner walls of the notches 37 forcing the nose 22 of the pawl 21 firmly into the can dog opening.

When the can is released and it is desired to remove the bar 15, the noses 22 may be released from these openings by forcing outwardly upon the weighted upper ends 24 so as to bring these pins against the outer end walls of these notches, swinging the pawls 21 toward one another.

In the form shown in Figure 4 the weighted upper end 24 of the pawl 21 does not bear the shoulder engaging nose 31, it being in the form of a separate section pivoted upon the same pivot 23 as the pawl 21. The weighted upper end 24, in this instance, acts to hold the pawl 24 continually in engagement, while the nose 22 falls by gravity into position beneath the shoulder 28. In this construction the piece upon which the nose is formed is made of sufficient weight to slightly overbalance the pawl 21 so that it is but loosely engaged in the openings 12 and the pawl 21 is provided with a shoulder 38 engaging the nose 22 when the pawl is fully engaged in the openings and forcing the pawl 21 from beneath the shoulder 28.

In this construction, as in the construction previously described, the nose 21 is removed from beneath the shoulder which it engages by the placing of strain upon the hoisting apparatus engaged in the eye of the weighted portion 24 of the pawl 21.

In Figure 1 I have disclosed a modification of the type of can dog at present in use. In the structure of my invention these can dogs consist of a tube 39 in the opposite ends of which are disposed spring pressed bolts 40 the springs 41 of which urge the ends of the bolts outwardly for engagement in the can dog receiving openings 12 of the can. In accordance with my invention I slot these bolts 40 adjacent the ends thereof, as indicated at 42, and extend through the walls of the tube 39 a pin 43 the ends of which project at opposite sides of the tube 39 and form a mounting for the arms of the forked lower end 44 of a pawl 45 bearing the shoulder engaging nose 31, this pawl 45 having the hook receiving opening 25 formed therein. The tube 39 is constructed centrally to support the air tube 19 in any desired manner. With this type of bar it will be obvious that when the bar is placed in position the bolts 40 will spring outwardly to engage in the openings 12 thus preventing upward movement of the bar with relation to the can. The weight of the pawls 45 will cause them to fall outwardly to bring the noses 31 beneath the shoulders 28 and maintain the can against upward movement, the engagement of the hooks 26 of the hoisting apparatus with the eyes of these pawls will, of course, tend to withdraw the pawls in the usual manner. In this form the construction of the lower end of the arms 44 of the pawls 45 is preferably such that they engage against the walls of the

can so that they limit inward movement of the upper walls of the pawls as shown in dotted lines.

From the foregoing it is believed to be obvious that a device constructed in accordance with the foregoing will provide a considerable saving in the operation of ice plants. Instead of having to remove a hold-down bar and then attach a can dog to the can, the can dog is already applied to the can and all that is necessary for the operator to remove is the usual air fitting from the air pipe 19 and attach the hoisting hooks in the openings 25. Thus the hold-down bar is combined with the can dog and pipe support as a unit and may be removed as such. It is further ordinarily necessary that before thawing out the ice from the can the air tubes and brackets associated therewith be removed. This means a considerable loss of time because the ice puller must wait a short length of time for the ice to thaw loose from the can before he can dump it, while with my apparatus the air drop tube bracket is combined with the can dog and hold-down bar and is employed in hoisting the ice so the ice can be conveyed to the thawing apparatus and the drop tube removed while the ice is being thawed.

In each construction above described some suitable means are provided for limiting the outward movement of the pawls 21 so that the noses thereof will not project sufficiently to engage in the walls 13. In Figures 4, 7 and 9, this limitation is accomplished by the actual engagement of the pawl with the wall of the can. In Figure 8 this limitation is maintained by the use of a lug 46 formed on the pawl 21 and engaging against the bottom of the channel bar 47. In Figure 1 this limitation is accomplished by the engagement of an operating finger piece 47 secured to the plunger and operating through a slot 48 formed in the tube 39, this finger piece engaging against the outer end wall of the slot to provide this limitation. This finger piece further serves as a means of withdrawal of the dog lug when the cross bar is to be removed.

Particular attention is directed to the fact that in each of the constructions above set forth I have provided a means for vertically supporting the air tube 19. In Figure 1 a vertical bore 49 is formed directly through the tube 39 to which the tube extends, the flange of the tube being preferably formed to engage with the tube 39 and prevent rotation of the air tube 19 and further to form a housing for a compressible gasket member 50 of any suitable construction. In the form shown in Figure 5 the guidance of the tube 19 is, of course, accomplished by the opening 51 of the plate 18, this opening being of a size to snugly fit the pipe 19. In the mounting shown in Fig-

ures 10 and 11 the bar 16, which in this instance is formed of wood, is provided with a bore 52 therethrough having at diametrically opposed points grooves 53 formed in the walls thereof. The upper end of the tube 19 is provided with a fitting 54 having a diameter equal to that of the bore 52 and having secured at diametrically opposed points vertical shoulders 55 for engagement in the grooves 53. This member includes a flange 56 for coaction with a compressible gasket 57. The engagement of the vertical shoulders or ribs 55 in the slots will prevent rotation of the pipe and tend to hold the same firmly in vertical position.

In the form shown in Figures 12 and 13, which is the form preferably employed when a channeled cross bar is employed, I seat within the channel a piece of rubber pipe 58 through which a vertical bore is formed having a diameter snugly receiving the pipe 19, the base of the channel being formed with a similar opening indicated at 59. In this construction the flange of the pipe is made of a diameter equal to the distance between adjacent faces of the channel bar so that sidewise movement of the pipe 19 is prevented.

Attention is directed to the fact that in each of the constructions employed a compressible gasket or element is disposed between an enlarged portion of the pipe and the bar through which the pipe extends for guidance. This gasket is important in that it permits a slight relative shifting of the can and bar after the cake of ice is frozen to thereby prevent the strain due to the shifting of the bar from falling upon the drop pipe. In event such shifting movement takes place, the drop or air pipe 19 is permitted to move due to the compression of this gasket.

As is evidenced by the various constructions illustrated and described, the device is capable of a considerable range of change and modification without materially departing from the spirit of my invention and I accordingly do not limit myself to such specific structure as hereinbefore set forth except as hereinafter claimed.

I claim:

1. In refrigerating apparatus, the combination with a water can adapted to be partially submerged in cooling fluid in a walled compartment, of a bar extending transversely of the can having withdrawable means engaging the can to prevent relative movement of the can and bar, withdrawable means engaging the walls of the compartment to prevent upward movement of the bar, the first named means being normally partially engaged with the can, and a connection between said means whereby withdrawal of the last named means to permit upward movement of the bar fully seats the

first named means so that the can is elevated with the bar.

2. The combination with a water can adapted to be partially submerged in brine in a walled compartment, of a bar extending transversely of the can and provided at each end thereof with a pair of pawls, one of said pawls being adapted for engagement in openings in the wall of the can to prevent upward movement of the bar with relation to the can, the other of said pawls being adapted for engagement with the wall of the compartment to prevent upward movement of the bar within the compartment, the last named pawl moving outwardly by gravity to engage the walls of the compartment.

3. The combination with a water can adapted to be partially submerged in brine in a walled compartment, of a bar extending transversely of the can and provided at each end thereof with a pair of pawls, one of said pawls being adapted for engagement in openings in the wall of the can to prevent upward movement of the bar with relation to the can, the other of said pawls being adapted for engagement with the wall of the compartment to prevent upward movement of the bar within the compartment, the last named pawl moving outwardly by gravity to engage the walls of the compartment, the walls of the compartment being formed to provide a downwardly facing shoulder beneath which the pawl engages.

4. The combination with a water can adapted to be partially submerged in brine in a walled compartment, of a bar extending transversely of the can and provided at each end thereof with a pair of pawls, one of said pawls being adapted for engagement in openings in the wall of the can to prevent upward movement of the bar with relation to the can, the other of said pawls being adapted for engagement with the wall of the compartment to prevent upward movement of the bar within the compartment, the last named pawl moving outwardly by gravity to engage the walls of the compartment, the last named pawls being swingable in the direction of the longitudinal axis of the bar, a connection between the last named pawls and the first named pawls forcing the first named pawls into engagement in openings of the can when the last named pawls are moved towards the center of the bar.

5. The combination with a water can adapted to be partially submerged in brine in a walled compartment, of a bar extending transversely of the can and provided at each end thereof with a pair of pawls, one of said pawls being adapted for engagement in openings in the wall of the can to prevent upward movement of the bar with relation to the can, the other of said pawls being adapted for engagement with the wall of the compartment to prevent upward movement

of the bar within the compartment, the last named pawl moving outwardly by gravity to engage the walls of the compartment, the last named pawls being swingable in the direction of the longitudinal axis of the bar, a connection between the last named pawls and the first named pawls forcing the first named pawls into engagement in openings of the can when the last named pawls are moved towards the center of the bar and withdrawing the first named pawls from engagement in the openings of the can when moved toward the ends of the bar.

6. In refrigerating apparatus, the combination with a water can adapted to be partially submerged in cooling fluid in a walled compartment, of a bar extending transversely of the can having withdrawable means engaging the can to prevent relative movement of the can and bar, withdrawable means engaging the walls of the compartment to prevent upward movement of the bar, the last named means being withdrawn from engagement upon movement thereof toward a common center and hoisting means including elements engageable with said withdrawable means and withdrawing the same upon application of strain thereto.

10 7. In refrigerating apparatus, the combination with a water can adapted to be partially submerged in cooling fluid in a walled compartment, of a bar extending transversely of the can having withdrawable means engaging the can to prevent relative movement of the can and bar, withdrawable means engaging the walls of the compartment to prevent upward movement of the bar, a drop pipe supported by the bar and having an enlargement above the bar, and a compressible element between the drop pipe and bar.

15 8. In refrigerating apparatus, the combination with a water can adapted to be partially submerged in cooling fluid in a walled compartment, of a bar extending transversely of the can forming a support for a drop pipe for the can and a means whereby the can may be withdrawn from the tank compartment, means interposed between the bar and a portion of the drop pipe limiting movement of the drop pipe through the bar by gravity but permitting further movement of the drop pipe through the bar when strain is placed upon the bar.

20 9. In refrigerating apparatus, the combination with a water can adapted to be partially submerged in cooling fluid in a walled compartment, of a bar extending transversely of the can having withdrawable means engaging the can to prevent relative movement of the can and bar, withdrawable means engaging the walls of the compartment to prevent upward movement of the bar, the last named means being withdrawn from engagement upon movement thereof toward a common center and hoisting means including elements engageable with said withdrawable means and withdrawing the same upon application of strain thereto.

25 10. In refrigerating apparatus, the combination with a water can adapted to be partially submerged in cooling fluid in a walled compartment, of a bar extending transversely of the can having withdrawable means engaging the can to prevent relative movement of the can and bar, withdrawable means engaging the walls of the compartment to prevent upward movement of the bar, the first named means being normally partially engaged with the can, and a connection between said means whereby withdrawal of the last named means to permit upward movement of the bar fully seats the first named means so that the can is elevated with the bar, the last named means being withdrawn from engagement upon movement thereof toward a common center and hoisting means including elements engageable with said withdrawable means and withdrawing the same upon application of strain thereto.

In testimony whereof I hereunto affix my signature.

ARTHUR H. HUTCHINSON.
